DEVICE FOR SHAPING METAL SHEETS

Basil Lermont, New York, and Arnold M. Wolf, Brooklyn, N. Y., assignors to Cairns Corporation, Brooklyn, N. Y., a corporation of Delaware

Application September 24, 1942, Serial No. 459,496

2 Claims. (Cl. 153—48)

This invention relates to devices for shaping metal and relates more particularly to devices for stretching, working and forming metal sheets into transversely and longitudinally curved shapes suitable for use in the construction of fuselages for aircraft, boat hulls and other structures having curved portions.

Many different types of devices have been used heretofore to convert initially flat sheets of metal into curved and angular shapes. The most widely used metal-shaping devices are die presses involving the use of accurately designed and fitted cooperating male and female die members. Such die presses are admirably suited for mass production operations, where great numbers of identical articles are to be produced. However, they have the disadvantages of being extremely expensive and difficult to manufacture, they require presses of great weight and size in order to apply the necessary pressure to deform the sheets into the desired shape, and because of the difficulty of manufacturing the die elements and replacing them in the presses, such die presses lack versatility in the manufacture of parts of varying shape.

It has been suggested that a single die member may be used to shape sheets into complementary forms. Such devices usually include mechanisms for gripping the edges of a sheet and a hydraulic ram or similar device which forces the die member against one side of the sheet to stretch the sheet beyond its yield point and cause it to conform to the contour of the die. Such single die presses have not been entirely satisfactory for the reason that a considerable waste of material results due to the edges of the sheet being retained in a plane while the remainder of the sheet is deflected from the plane, thereby necessitating extensive trimming away of the edges to produce the desired curvature of the edges of the sheet. Moreover, uncontrollable stresses and buckling of the sheets result from the differences in shape of the die and the retaining means. Nevertheless, the use of a single die would have marked advantages in the production of compound, curved sheets, if it were possible to control more closely the amount the sheets are stretched, the final shape of the sheets and the stresses exerted on the sheets.

An object of the present invention is to provide a device for shaping sheet metal into curved forms over a single or multiple die member or form with a minimum waste of material.

Another object of the invention is to provide

a sheet metal shaping device in which the sheet metal is stretched under controlled conditions to correspond to the shape of the die member, members or form.

5 A further object of the invention is to provide a device for shaping sheet metal in which the forms or die members may be easily interchanged and the means for gripping the sheets of metal are arranged in relation to the forms or die members to provide a predetermined allocation of the metal, thereby increasing the extent to which the sheet may be worked before reaching its critical point and resulting in fracture.

10 A further object of this invention is to provide a flexible device for shaping sheet metal in which the gripping means may be adjusted to vary the angles of pull in order to provide a predetermined allocation of draw radii thereby reducing the concentration of stresses at the 15 draw radii and more uniformly distributing the elongation of the metal through the sheet.

20 Other objects of the invention will become apparent from the following description of typical forms of devices embodying the present invention.

25 In accordance with the present invention, a device is provided which includes opposed pairs of jaws for gripping the opposite edges of a sheet of metal and tensioning the sheet over an 30 interposed form of predetermined contour to stretch the sheet into a shape corresponding to the contour of the form. More particularly, the device includes gripping jaws that are moved individually or in unison to stretch and pull the 35 sheet into tight engagement with a fixed or movable form or forms and thereby stretch the sheet beyond its yield point to cause it to become curved and form-retaining in a permanent set. The jaws are of such shape that they correspond 40 substantially to the desired curvature of the sheet, thereby avoiding the introduction of stresses at angles to the direction of stretching of the sheets and rendering substantially the entire sheet usable. The gripping and stretching means 45 may be utilized in combination with a ram to provide increased flexibility of operation.

For a better understanding of the present invention, reference may be had to the accompanying drawings in which:

50 Figure 1 is a view in side elevation of a typical form of device embodying the invention;

Figure 2 is a top plan view of the device;

Figure 3 is a view in section of one of the 55 clamping jaws, taken on line 3—3 of Figure 2; and

Figure 4 is a view in section taken on line 4-4 of Figure 1.

The device chosen for purposes of illustration includes a base member 10 formed of two side members 11 and 12 of generally U-shaped cross-section that are adapted to rest upon a floor or other suitable support. The side members 11 and 12 are connected by transverse braces 12a to form a rigid, sturdy frame.

Between the side members 11 and 12 is mounted a hydraulic ram 13 having a platen 14 thereon for supporting a form or die member 15. The form 15 has a flat base 15a and an upper surface 15b of a shape corresponding to the shape of the sheet to be produced. As illustrated, the upper surface 15b of the form 15 may have transverse and longitudinal curvatures, thereby providing a compound curved surface. It will be understood that the shape of the surface 15b may be varied widely and may consist of any desired combination of curvatures. The form 15 may be made of wood, concrete, plastics, metal or combinations of the same, or any other type of material that is capable of withstanding high compressive stresses, without appreciable distortion. Hard wood is entirely suitable for the reason that it will not scratch the sheets, is easily worked into the desired shape and is capable of withstanding the stresses applied thereto during the shaping operation.

At opposite ends of the base member 10 are mounted adjustable gripping and stretching members 16 that are adapted to grip the ends of a sheet S of metal and stretch it over the form 15. Each of the gripping and stretching members 16 includes a pair of levers 17 and 18 connected to opposite ends of a shaft 19 that is journaled in suitable bearings 20 adjacent each end of the base member 10. The upper ends of the levers 17 and 18 are connected to a rigid box-like member 21 that is formed of an upper plate 21a, a lower plate 21b and interposed partitions or braces 21c. The member 21 is also provided with a front wall 21d that is spaced inwardly from the front edge of the plate 21b and has a plurality of upwardly projecting, spaced-apart hinge elements 21e thereon that extend above the upper plate 21a.

In front of the wall 21d is detachably mounted a lower jaw member 22 for gripping the end of the sheet S. The lower jaw 22 may be secured to the bottom plate 21b and the front wall 21d by means of any suitable sturdy detachable fastening means such as, for example, bolts.

A cooperating gripping jaw member 23 is detachably mounted on a plate 24 that is provided with hinge elements 24a adapted to be received between the hinge elements 21e and retained in pivotal relationship thereto by means of a hinge pin 25. The jaw 23 is also detachably connected to the plate 24 by means of detachable fastenings such as, for example, bolts.

The mechanism for opening and closing the jaws may consist of the toggles 26 having their outer ends pivotally connected to the plates 21b and 24 and their inner ends pivotally connected to a plunger 27 of a hydraulic ram 28. The hydraulic rams 28 may be supported on the front wall 21d and are connected to a suitable source of fluid pressure. When the plunger 27 is projected, the toggles 26 are straightened, thereby forcing the jaws 22 and 23 together to firmly grip the ends of the sheet S. When the plunger 27 is retracted, the toggles 26 are collapsed, thereby causing the jaws 22 and 23 to separate.

The jaws 22 and 23, illustrated, are curved from end to end, the lower jaw being convex and the upper jaw being concave. These curvatures are substantially the same as the curvatures of the adjacent ends of the form 15 so that there will be no tendency of the sheet to buckle adjacent the ends of the form during the stretching operation.

In order to stretch the sheet of metal over the form 15, means is provided for moving the clamping and gripping elements 16 pivotally with relation to the base member. The means for moving the jaws, illustrated in the drawings, may consist of suitable pairs of hydraulic rams including cylinders 29 pivotally connected to the base member 10. The cylinders 29 are provided with pistons having piston rods 30 thereon that are provided with bifurcated end portions 31 that straddle the levers 17 and 18 and are secured thereto by suitable pivot pins 32. The hydraulic rams 29 are connected to a suitable source of liquid under pressure so that the piston rods 30 may be projected into the positions shown in Figure 1 with the clamping and gripping elements in their innermost position, or retracted to move the clamping and gripping elements 16 apart in order to stretch the sheet of metal gripped therebetween. It will be understood that the liquid in the cylinders 29 may be controlled by suitable valves so that gripping and stretching elements 16 may be moved selectively.

In operation, a form 15 of the desired contour is positioned on top of the base member, the jaws 22 and 23 of each of the gripping members 16 are separated and the ends of a sheet of metal are inserted therebetween. The jaws 22 and 23 are then forced together by means of the rams 28 to firmly grip the ends of the sheet of metal.

When the sheet is gripped by the gripping members 16, fluid under pressure is delivered into the hydraulic rams 29 and the gripping members 16 are moved apart, thereby stretching the sheet and as the jaws move apart and downwardly, pulling the sheet firmly into contact with at least a portion of the surface 15b of the form 15. The ram 13 may then be operated to force the form 15 against the sheet S until the sheet has been stretched sufficiently to be form-retaining and to fit closely over the form. Inasmuch as the stretching operation stretches the sheet beyond its yield point, there is no tendency for the sheet S to coil or spring back upon itself or to return to its initially flat shape. The sequence of operations can be varied widely depending upon the shape of the form 15 and the amount a sheet of metal must be stretched to shape it to the contour of the form. In some cases, the entire stretching operation may be conducted by movement of the gripping elements 16 while in others the stretching may be conducted by movement of the ram 13 with the gripping elements 16 moving inwardly to feed the metal under tension to the ram. In this latter type of operation, the initial tension may be created by separation of the gripping elements with the ram out of engagement with the sheet S. With a sheet initially stressed, loose material will not gather nor will the sheet buckle at the uncontacted region when the ram is forced into contact with the sheet. Through a choice of the proper hydraulic circuits the action of the gripping jaws may be synchronized to feed the metal at a desired tension in accordance with the elevation of the form or die members placed on the platen of the ram in

order to assure proper feeding of the metal to the form.

When a form of different contour, that is, of different transverse or longitudinal contour, is used, it may be necessary to replace the jaws 22 and 23 of the gripping devices 16 with other jaws of different curvature in order to correspond to the curvatures of the ends of the form. Inasmuch as the jaws are detachable, this change is readily made, thereby permitting the device to be used in producing sheets of varying contour.

While the preferred form of the device has been described above, it will be understood that the device is susceptible to considerable modification without departing from the invention. For example, the actuating means for the jaws 22 and 23 and the gripping members 16, as a whole, may be any equivalent of the hydraulic rams disclosed, such as, for example, electrically operated jacks or the like. Additional adjustments may be provided for the clamping and stretching devices, for example, the levers 17 and 18 may be made extensible in order to adjust the ends of the sheets with relation to the ends of the form. The base member need not be a unitary construction, but may be made up of a plurality of parts mounted upon a suitable foundation, as may be desired and the entire device may be inverted, if desired. Therefore, the form of the invention disclosed, should be considered as illustrative only, and not as limiting the scope of the following claims.

We claim:

1. An apparatus for shaping sheets of metal into transversely and longitudinally curved form comprising a base member, a form having a convex surface supported adjacent to said base member, means for moving said form toward and away

from said base member, a pair of levers at each end of said form, means pivotally connecting the lower ends of said levers to said base member, a pair of pivotally connected jaw members supported at the upper ends of each pair of levers for gripping an edge portion of a sheet of metal, said jaw members being complementally curved to conform substantially to the curvature of the ends of said form adjacent thereto, and means for rocking said pairs of levers about said pivot means for moving each pair of jaw members relatively to said form to stretch said sheet over said form and into engagement with said convex surface.

2. An apparatus for shaping sheets of metal into transversely and longitudinally curved form comprising a base member, a form having a convex surface supported adjacent to said base member, a hydraulic ram supporting said form for movement toward and away from said base member, a pair of pivotally connected jaw members adjacent opposite ends of said form for gripping an edge portion of a sheet of metal, said jaw members being complementally curved to conform substantially to the curvature of the ends of said form adjacent thereto, arms pivotally mounted on said base member and extending upward therefrom above said form, said jaw members being carried by said arms and pivotally movable with respect thereto on movement of said arms, and means connected to said base and arms for moving said arms in opposite directions outwardly and downwardly with respect to said form whereby said jaw members are moved relative to said form to stretch said sheet over said form and into engagement with said convex surface.

BASIL LERMONT.
